(75) Inventor: **Stephanie Cobigo**, Eindhoven (NL)

* cited by examiner

(73) Assignee: **Koninklijke Philips Electronics N.V.**,
Eindhoven (NL)

Primary Examiner—Nelson C. Holtje
(74) Attorney, Agent, or Firm—Ernestine C. Bartlett

(**) Term: **14 Years**

(57) **CLAIM**

(21) Appl. No.: **29/178,442**

The ornamental design for a signal receiving device, as
shown.

(22) Filed: **Mar. 26, 2003**

DESCRIPTION

(30) **Foreign Application Priority Data**

Oct. 15, 2002 (WO) DMA/005 856
(51) LOC (7) Cl. **14-03**
(52) U.S. Cl. **D14/496; D10/104**
(58) Field of Search D14/496, 159,
D14/137; D10/104; 352/34; 360/17
